CLAIM

(21) Appl. No.: **29/225,079**

The ornamental design for a rechargeable emergency light
with radio, as shown and described.

(22) Filed: **Mar. 9, 2005**

DESCRIPTION

(30) **Foreign Application Priority Data**

Jan. 17, 2005 (HK) 0500108

FIG. 1 is a front view showing my new design.

(51) LOC (8) Cl. **26-02**

FIG. 2 is a rear view thereof.

(52) U.S. Cl. **D26/38**

FIG. 3 is a side end view thereof.

(58) Field of Classification Search D26/37-50;

FIG. 4 is other side view thereof.

362/157, 158, 171-174, 183-208

FIG. 5 is an underneath view thereof.

See application file for complete search history.

FIG. 6 is plan view thereof.

(56) **References Cited**

FIG. 7 is a side view with plug showing thereof.

U.S. PATENT DOCUMENTS

FIG. 8 is a rear view with plug showing thereof; and,
FIG. 9 is an underneath view with plug showing thereof.
The surface(s) or portion(s) of the article not shown in the
drawing or described in the specification form(s) no part of
the claimed design.
